ELI HAKEY, OF SWANTON, VERMONT.

CLAMP ATTACHMENT FOR WRENCHES.

1,157,383.

Specification of Letters Patent. Patented Oct. 19, 1915.

Application filed June 4, 1914. Serial No. 842,891.

To all whom it may concern:

Be it known that I, ELI HAKEY, a citizen of the United States, residing at Swanton, in the county of Franklin and State of Vermont, have invented a new and useful Improvement in Clamp Attachments for Wrenches, of which the following is a specification.

This invention relates to wrenches, and 10 more particularly to a combination wrench and clamp.

One of the principal objects of the invention is to provide a combination wrench capable of use as a monkey wrench, a pipe 15 wrench, or a clamp.

Another object of the invention contemplates the provision of a wrench with a clamp mechanism carried by the movable jaw of the wrench and capable of adjustment relatively to the fixed wrench jaw.

A further object of the invention is to provide a clamp mechanism adapted to be carried by one of the jaws of a wrench and adjustable with relation to the other jaw, the parts being removable so that the clamp mechanism may be taken off, and the handle and shank of the wrench being so constructed that the handle may be removed to provide for greater adjustment of the 30 wrench and clamp.

A further object of the invention is to provide a mechanism of the class described, which will be simple, durable, efficient in operation, and inexpensive to manufacture.

With these and other objects in view which will become apparent as the description proceeds, the invention resides in the construction, combination and arrangement of parts, hereinafter more fully described, and claimed and illustrated in the accompanying drawing, in which like characters of reference indicate like parts throughout the several figures, of which—

Figure 1 represents a side elevational view of a wrench equipped with an attachment constructed in accordance with my invention. Fig. 2 represents a bottom plan view thereof. Fig. 3 represents a vertical transverse sectional view taken on the plane indicated by the line 3—3 of Fig. 1. Fig. 4 represents a view similar to Fig. 3 taken on the plane indicated by the line 4—4 of Fig. 1, and Fig. 5 represents an elevational view of one end of the shank showing the same with the handle removed.

Referring more particularly to the draw-

ing, the wrench includes a fixed jaw 5, secured to the outer end of a flat shank 6, having a central longitudinal slot 7 provided therein and having its upper edge provided with teeth 8 for forming a rack, said shank capable of having secured to the end opposite jaw 5, a handle, comprising side pieces 9 connected at the rear ends by a cross piece 10 to which the side pieces are secured, said cross piece 10 adapted to fit within a notch 11 in the end of shank 6, said side pieces when in position being connected by a bolt 12 extending through openings in the side pieces and through slot 7 at the end 13 thereof. When the handle is in position on the shank, the upper edges of said handle are flush with the upper edges of teeth 8 so that the latter do not project beyond the handle.

A movable jaw 14 is provided, through an opening 15 in the upper end whereof shank 6 extends, whereby the jaw is movable longitudinally of said shank, and extending each side of the upper end 16 of the jaw is a tapered guide plate 17 extending parallel with the shank and having its lower surface plain and adapted to slide over the upper edge of teeth 8 so that the movable jaw is securely braced against wedging movement relatively to the shank. The movable element 14 is in the nature of a slidible wrench jaw and is adapted to be used as such when the clamp jaw is unattached from the wrench.

A pawl 19 having depending teeth 20, is provided with spaced arms 21 pivoted at 22 on each side of the rear end of guide plates 17, and said pawl carries a thumb piece 23 extending upwardly from the pawl, said thumb piece serving as a bearing for one end of a coil spring 24, whose other end bears in a recess in the rear end of plate 17 as at 25, the function of spring 24 being to normally maintain the teeth carried by the pawl in engagement with rack teeth 8, whereby the movable jaw 14 is normally held against movement in adjusted position relatively to the stationary jaw 5. By pressing against thumb piece 23 pawl 19 may be raised, whereby the movable jaw may be adjusted relatively to the stationary jaw, and upon releasing the pawl the latter will engage the teeth for maintaining the jaws in adjusted relation.

A clamp jaw 26 is disposed between the movable and stationary jaws, and is pro-

vided with a pair of spaced arms 27 at its upper end, which embrace the shank 6, and are connected by a removable bolt 28 extending through slot 7 in the shank, whereby the 5 jaw is guided, and said jaw on one side is provided with a guide plate 29 extending rearwardly and slidably engaging one outer face of jaw 14, said guide plate 29 provided with a longitudinally disposed slot 30, 10 through which extends a bolt 31 carried by jaw 14, whereby the plate is guided in its movement relatively to the jaw.

In order to operate the clamp jaw, a cam lever 32 is provided which has an enlarged 15 head 33 at its lower end, which head is pivoted on bolt 31 on the outer face of guide plate 29, the lever handle 34 extending above the wrench in position to be readily grasped by the operator. An arcuate slot 35 is provided in the head 33, and said slot is adapted 20 to work over a roller 36 journaled on a pin 37 which is secured to guide plate 29, whereby as will be readily understood by moving the cam lever toward or away from stationary jaw 5, the clamp jaw will be 25 moved away from or toward said jaw. On the beveled upper edge 38 of lever head 33, is provided a rack 39, and a keeper 40 pivoted on a bolt 41 which extends through slot 30 7 and is carried by the movable jaw 14, is adapted to co-act with rack 39 in the manner indicated in Fig. 1 in preventing movement of the clamp jaw away from jaw 5, when the clamp jaw has been forced into engagement 35 with an object to be clamped between the clamp jaw and said immovable jaw, said keeper being provided with a tooth 42 adapted to engage the teeth of the rack 39. By lifting keeper 40 by means of a 40 thumb piece 43 carried thereby, said keeper will be moved out of engagement with rack 39.

The clamp mechanism is carried by the movable jaw 14, and may be moved bodily with said jaw, and the clamp mechanism 45 having by adjustment of jaw 14 been placed in suitable position to engage the object to be clamped against jaw 5, the cam lever may be operated to move the clamp jaw against the object for clamping the same, the keeper 50 40 being operated as stated before to hold the clamp jaw in adjusted position.

The wrench can be used either as a clamp or an ordinary wrench while the clamp mechanism is in place on said wrench, but 55 it will be desirable when the wrench is to be

used as a pipe wrench, to remove the clamp mechanism, and this may be done by removing the bolt 28 connecting the arms 27 of the clamp jaw through slot 7, and by removing the bolt 31 which connects the cam lever and 60 guide plate 29 with the movable jaw. When the wrench is used as a pipe wrench the movable jaw 14 may be forced into engagement with the pipe by hand, and held in adjusted position by reason of pawl 19. 65

The wrench handle as is obvious necessarily acts as a limit to the range of movement of jaw 14 away from jaw 5, and consequently limits the range of movement or adjustment of the clamping mechanism. 70 Should it be desired to increase the ordinary range of movement of jaw 14 and the clamping mechanism, the handle may be removed by removing bolt 12, so that the parts mentioned may have the play of the entire length 75 of the shank, and may be held in adjusted position throughout the length of the shank since the rack teeth 8 extend clear to the outer end thereof.

The opposing surfaces of jaws 5 and 14 are 80 provided with biting teeth 44 for biting into the surface of a pipe or other object upon which the wrench is being used, while the engaging face of clamp jaw 26 is smooth.

Although I have described the preferred 85 embodiment of my invention, I may desire to make such changes in the construction, combination and arrangement of parts thereof as do not depart from the spirit of the invention and the scope of the appended 90 claim.

I claim:—

The combination with a wrench having a shank, a movable jaw and a stationary jaw, of a clamp jaw arranged between the movable and stationary wrench jaws, a plate carried by the clamp jaw extending alongside the movable jaw and provided with a longitudinal slot, a removable pin carried by the movable jaw and extending through the slot, 100 a cam lever pivoted upon the pin, cooperating means between the cam lever and clamp jaw for adjusting the latter relatively to the stationary jaw, and means for maintaining the clamp jaw in adjusted position relatively 105 to the stationary jaw.

ELI HAKEY.
